UNITED STATES PATENT OFFICE.

WALTER GEORGE CROSTHWAITE, OF LEEDS, ENGLAND, ASSIGNOR TO DANIEL B. STREET, OF WASHINGTON, DISTRICT OF COLUMBIA.

FIRE-BAR FOR FURNACES.

1,025,128.

Specification of Letters Patent.

Patented May 7, 1912.

Application filed January 21, 1908. Serial No. 411,946.

To all whom it may concern:

Be it known that I, WALTER GEORGE CROSTHWAITE, a subject of the King of Great Britain and Ireland, residing at York 5 Street Mills, Leeds, in the county of York and Kingdom of England, have invented new and useful Improvements in Fire-Bars for Furnaces, of which the following is a specification.

10 This invention has reference to improvements in the firebars for furnaces constructed in accordance with the specification of United States Letters Patent originally granted to Thomas Westerby and Walter 15 George Crosthwaite under No. 693,634, dated 18th February 1902, and reissued on May 23rd 1905 to Walter George Crosthwaite, surviving inventor, and the Crosthwaite Fire Bar Syndicate, Limited, of Leeds, England, assignee, 20 by mesne assignments, of Thomas Westerby, deceased, and the said Walter George Crosthwaite, under No. 12,351. In said patent, the firebars are arranged transversely in the furnace and each bar is provided with two sets 25 of air holes or conduits. The bars are arranged to interlock together for forming the said air holes which run longitudinally from the front of the furnace to the bridge at its rear end. One set of air holes supplies air to or 30 beyond the bridge. The other set of air holes communicates with fan tail openings for conveying the air passing through the said holes to the upper surface of the firebars and through the burning fuel. The 35 said fantail openings in the herein before mentioned specification are described as being formed partly in one firebar and partly in a second contiguous firebar so that when the two firebars are placed longitudinally 40 together, a complete fantail opening is formed. Further, in the aforesaid patent means are described for using a longitudinal semi-circular trough in place of the means employed for interlocking the bars together 45 and for preventing the escape of air to the ash pit.

Now the object of this invention is to provide means whereby the fantail openings are each formed wholly in one firebar, instead 50 of in the two bars as described in the said patent, and further each firebar may be arranged, if so desired, to be formed in two longitudinal portions.

55 In the drawings hereunto annexed:—Figure 1 is a front elevation of a firebar con-

structed according to this invention. Fig. 2, a transverse section of a plurality of firebars on the line 2—2 of Fig. 1. Fig. 3, a similar view on the line 3—3 Fig. 1. Fig. 4, a transverse section of a plurality of firebars on line 4—4, Fig. 1. Fig. 5, a transverse section of a plurality of firebars showing a modified construction. Fig. 6, a plan of a group of firebars, one of these firebars being separated from said group. 65

Like parts in all the views are marked with similar letters of reference.

A are the firebars which are of a similar outer contour to those described and illustrated in the hereinbefore mentioned patent. 70 The firebars A may or may not be provided with feet A¹. Each firebar is provided with a number of holes or conduits which pass transversely through the firebar for forming, when a number of such bars are placed together,—side by side,—the two sets of holes B, B, C, C. Through the holes B, B, C, C, air or air and steam may be forced. The bar is also provided with a number, three (more or less) of semi-circular recesses 80 D alternately arranged in its sides into which fit similarly arranged projections E formed on a second bar, which interengage and form transverse air conduits when the firebars are placed longitudinally together. 85 The recesses F and projections G may be either circular or other approved form. In all cases when a semi-circular recess and projection is used it is arranged at the lower portion of the air hole or conduit for preventing any escape of air into the ash pit. 90

The above described parts are of a similar construction to those described and illustrated in the hereinbefore mentioned patent. Instead of forming the fantail openings H 95 which are at a right angle to and communicate with one set of holes B, B, partly in each of two of the firebars as described and shown in the said prior patent, in the present invention one or more fantail openings 100 H is or are formed wholly or completely in one and the same bar. That is to say, each fantail or fan shaped opening H is in the form of a recess, formed, say, wholly in one face or side of each firebar as shown at Figs. 2 and 3. Or when more than one fantail opening H is formed in a firebar they are preferably arranged alternately on opposite sides. Each fantail or fan shaped recess H flares upwardly, as shown in Fig. 1, but the 110

width of said opening is greatest transversely at its bottom, or at its point of communication with the hole B, as shown in Figs. 2, 4 and 5. Under this construction the recesses H are long and narrow at the top ⁵ a of the firebar, and shorter longitudinally and wider transversely of said bar at their point of communication with the holes B, B. The recess H,—with the exception of being formed wholly in a single firebar, instead of in two such bars,—is of a similar shape and performs the same functions as the fan shaped openings described in the said prior patent. The part of a firebar which abuts ¹⁰ 15 against the side of one in which are fantail recesses is provided with a plain flat surface that forms the second longitudinal side or portions for closing or covering the open side of each fantail opening H. It may also be recessed at D and F, as at Figs. 3 and 4, to receive the semi-circular or circular projections E and G for interlocking purposes. In some cases, as in Figs. 1, 2, 3 and 4, the recesses D, F, are formed in the same side ²⁰ 25 as the fantail recesses H. In other cases, as in Fig. 5, the said openings are formed in the opposite side of the firebar to the recess H.

When desired, the firebar B is divided ³⁰ 35 longitudinally into two parts—that is to say, into an upper portion 1 and a lower portion 2, at or about, or a little above the axes of the openings B. The upper portion 1 of each firebar is arranged to rest upon the lower portion 2, as at Fig. 5. The two portions of each firebar may, or may not, be bolted or otherwise fastened together.

I claim:

1. A firebar provided with transverse ⁴⁰ 45 openings therethrough to form uninterrupted air passages when a series of said firebars

are associated to form a grate, other openings alternating with said transverse openings in the firebar connected each with a fan shaped air duct leading upwardly to the top ⁴⁵ of said firebar and successively disposed on opposite sides of the firebar, said fan-shaped air duct being recessed wholly in one side of the firebar, the side opposite said recess being a plane surface, and flanges projecting ⁵⁰ from alternate sides of the firebar and partly encircling the under half of the transverse openings, the side of the bar opposite said flanges having recesses therein of similar shape. ⁵⁵

2. A firebar provided with transverse openings therethrough to form uninterrupted air passages when a series of said firebars are associated to form a grate, other openings alternating with said transverse openings in the firebar connected each with a fan-shaped air duct leading upwardly to the top of said firebar and successively disposed on opposite sides of the firebar, said firebar being formed of two sections separable in a ⁶⁰ ⁶⁵ plane parallel to the upper surface of the firebar and approximately through the axes of the transverse openings connected to the fan shaped air duct, said fan shaped air duct being recessed wholly in one side of the ⁷⁰ firebar, the side opposite said recess being a plane surface, and flanges projecting from the under section of the firebar encircling on one side thereof the depressions forming the lower portions of the transverse openings, the side of the bar opposite said flanges having recesses therein of similar shape. ⁷⁵

WALTER GEORGE CROSTHWAITE.
